ATTORNEY.

UNITED STATES PATENT OFFICE.

CHARLES F. THATCHER, OF PROVIDENCE, RHODE ISLAND.

FASTENER FOR BOTTLE-STOPPERS.

1,240,511.

Specification of Letters Patent. Patented Sept. 18, 1917.

Application filed April 19, 1917. Serial No. 163,141.

To all whom it may concern:

Be it known that I, CHARLES F. THATCHER, a citizen of the United States, residing at Providence, in the county of Providence and 5 State of Rhode Island, have invented a new and useful Improvement in Fasteners for Bottle-Stoppers, of which the following is a specification.

This invention relates to certain new and 10 useful improvements in fasteners for bottle stoppers, and it resides in a simple and efficient retaining device, preferably formed of wire, for holding glass stoppers in position.

Bottles containing alcoholic beverages or 15 compositions likely to ferment usually have means for releasing the excess of gas, and it is a further aim of this invention to provide a retaining device for returning the glass stopper to its seat to insure against 20 the loss of the contents of the bottle.

In the drawing forming a part of this application—

Figure 1 is a side elevation of the retaining device applied to the neck of a bottle. 25 Fig. 2 is a front view of the stopper fastener in operative position.

Fig. 3 is a top plan view thereof, and

Fig. 4 is a perspective of the invention, 30 *per se*.

The retaining device is especially adapted 35 to use in connection with bottles having cork rings in their mouths and co-operating glass stoppers so it has, therefore, been illustrated on the neck of a bottle of this type in the accompanying drawing in which the numeral 1 designates the bottle, in fragment, 2 the cork ring in the mouth or neck thereof, 3 the glass stopper, which has a depending plug 4 passing through the ring, and 5 the 40 stopper fastener or retaining device.

This retaining device consists of a single length of wire bent centrally in the form of a cross bar 10, and then the end portions are bent downwardly at an acute angle as 45 at 8 to form substantially parallel arms 9—9. The arms 9—9 are then bent rearwardly in the form of a semi-circle or U to provide a neck embracing base or clamp 6—6 adapted to engage the neck of the bottle 50 immediately below an exterior peripheral bead or shoulder 7 thereon. The acute angular bends 8 occur slightly beyond the center of the bottle, and the arms 9—9 incline rearwardly over the neck clasp 6—6 to dis- 55 pose the cross bar 10, substantially diamet-

rical of the top of the glass stopper, as depicted in Figs. 1 and 3. In this connection it will be noted that the upper surface of the stopper is slightly spherical or round and that the cross bar being substantially in 60 a horizontal plane engages the surface at its center and by reason of the retainer being of spring metal provides for a slight yielding of the stopper during the escape of gas. 65

In practice the device is applied by positioning the cross bar 10 centrally of the top of the stopper, and swinging the clasp 6 downwardly and transversely of the neck of the bottle during which action the arms of 70 the clasp will spring outwardly into a position for anchoring the retaining device to the neck of the bottle.

To remove the retaining device the clasp is used as a handle and lifted or swung outwardly away from the bottle until the former slips over the shoulder 7 when it may readily be lifted off. 75

The device is preferably made from wire possessing sufficient resiliency to accomplish 80 the desired results, since in applying the device the clasp is sprung over the shoulder 7 and simultaneously to a greater angular relation with the arms 9—9 in order to exert a downward pull on the stopper and the 85 arms 6—6 yield during the application of the device.

After any gas surplus has escaped the stopper is returned to its seat by the resilient 90 nature of the device.

The device may be economically manufactured in an expeditious manner and will be found very efficient as a retaining device or fastener for glass stoppers, being formed along simple and durable lines. 95

Having thus described my invention what I claim as new and desire to secure by Letters Patent is—

In combination with a receptacle having an exterior shoulder about its neck and a 100 stopper for the receptacle having a convex top, a fastener for the stopper formed of a single length of resilient wire bent centrally to provide an integral and diametrical straight bar engaging the convex top of the 105 stopper only at its center, and extending beyond the stopper, the outer ends of the bar being downturned into parallel arms spaced from the stopper and being straight throughout their lengths, said arms inclined 110

from the diametrical plane of the receptacle and having their lower ends bent acutely angular to form neck-embracing members the free terminals of which are curved about the neck of said receptacle beneath the shoulder.

In testimony whereof I have signed my

name to this specification in the presence of two subscribing witnesses.

CHARLES F. THATCHER.

Witnesses:
